Primary Examiner — Robin V Webster*Assistant Examiner* — Rachel Voorhies(74) *Attorney, Agent, or Firm* — Volpe and Koenig, P.C.(57) **CLAIM**

The ornamental design for a stream from fluid distribution equipment, as shown and described.

DESCRIPTION

FIG. 1 is a top perspective view of the stream according to my design;

FIG. 2 is a front view of the stream of FIG. 1, the rear view being identical thereto;

FIG. 3 is a left side view of the stream of FIG. 1, the right side view being identical thereto;

FIG. 4 is a top plan view of the stream of FIG. 1; and, FIG. 5 is a bottom view of the stream of FIG. 1.

The broken line showing of the fluid distribution equipment illustrates the environment of the claimed design and forms no part thereof. The broken line showing of the stream illustrate portions of the stream which form no part of the claimed design.
